UNITED STATES PATENT OFFICE.

GILBERT S. FLETCHER, OF WATERTOWN, MASSACHUSETTS.

CONTAINER FOR FRAGILE ARTICLES.

Application filed April 17, 1926. Serial No. 102,760.

This invention relates to improvements in containers for fragile articles. It is herein illustrated and described in its application to egg containers, but its use is not limited 5 to this, for the shape and size of a container embodying the principles of the invention can be varied to accommodate other frangible things as, for example, incandescent lamp bulbs or glass shades.

10 In packing eggs and other articles for safe and economical shipment it is desirable that each be sufficiently protected whether shipped alone or in quantity with others, as, in the case of eggs up to a gross or more. 15 Moreover, the protection should continue until the article is removed from its container by the ultimate consumer or user.

It is among the objects of the present invention to produce a container capable of 20 satisfying the requirements suggested, one which will have low first cost, be light in weight and which can be used repeatedly. It is a feature that the container can be cut and initially formed from sheet stock of some- 25 what elastic material, such as pasteboard, strawboard, other pulp-board or medium weight paper, and be sent to the packer in a substantially flat shape with one container nesting closely against another, thereby to 30 save space during transmittal and while in storage waiting to be used.

A further and important feature is that when a flattened container is removed from the pile and its center slightly pressed it will 35 spring into enclosing form, ready to receive the thing it is designed to protect.

These objects and the features which characterize the construction herein disclosed are attained by cutting or stamping from a sheet 40 of suitable material a one-piece blank with scored lines indicating where the folds are to be made. After being so folded to a rectangular egg-enclosing shape the container may be tempered in a mold if it appears desirable. 45 Whether tempered or not, after folding the container is opened and laid in a flattish form resembling a Greek cross with its center and extremities slightly raised and convex upward. In this condition it may be 50 nested with others similarly opened, and packed for distribution in commerce. Upon being laid out on a table one by one, and touched at the center with a slight pressure, as by one's finger, the center will spring 55 downward, snapping past the plane position, and the sides spring upward and tend to re-

main in concave or egg enclosing shape. Suitable openings in the blank, one at its center and others in its extremities, which later fold over the egg, enable an egg in the 60 container to be inspected.

Such an empty container, with others, can be placed in a box suitably proportioned to hold the number desired to be used, with a nice fit. The egg can then be inserted 65 in the top of each individual container, which will yield sufficiently to allow the egg to enter and then will snap back into its formed shape, locking the egg within and protecting it from external pressures. The 70 box thus loaded can be sent to the consumer or to a retailer. When an egg is to be used, a container is first lifted from the box, whereupon its four sides will naturally spread outward and downward, so that the 75 egg may be freely removed. The container thus emptied may be stored in its open or flattish shape, and others added thereto and nested therewith until a sufficient number are thus collected to warrant their return to 80 the producer, for another packing and shipment of eggs.

It is intended that the patent shall cover by suitable expression in the appended claims whatever features of patentable novelty exist in the invention disclosed. 85

In the accompanying drawing:

Figure 1 shows a blank from which a container embodying the invention may be formed; 90

Figure 2 is a perspective of the blank after folding, showing the container in open or "flattish" position;

Figure 3 is another perspective, showing the container in its closed or egg-enclosing 95 position;

Figure 4 is an elevation of a container with egg, in section on line 5—5 of Fig. 5;

Figure 5 is a plan showing containers with contents in a packing box; 100

Figure 6 is a blank from which a modified form of container can be made;

Figure 7 is a perspective of the container formed from the blank of Fig. 6;

Figure 8 is a plan of the center portion of 105 a modified form of blank, preferable when paper is used; and

Figure 9 is a perspective of the portion of Figure 8, showing the bottom folded, the container being inverted. 110

Referring to the drawings, it will be seen that the individual containers are of such

shape as to inclose an egg with eight surfaces of contact, four at each end portion of the egg, and with each surface tending to dissipate its pressure through the arch structure 5 of the egg shell. The surfaces which bear against that part of the egg which is toward its point are numbered 10, their inner or bottom ends forming the sides of an opening 12, cut in the center of the blank. The outer 10 edges of these four surfaces adjoin the four surfaces 14 which bear against the larger end of the egg. The individuals of each group of four surfaces are set obliquely, converging toward the respective end of the egg. Having 15 in mind that it is planned to make the containers of elastic material, it can now be seen that the egg is gently supported by eight elastic surfaces, 10, 14, capable of yielding a little in case of any shock being transmitted to the egg; that consequently under 20 ordinary circumstances only one-fourth of the weight of the egg is borne at any one of the points of contact; and that the obliquity with which the planes of support approach 25 each other is such that neither tip end of the egg can touch bottom.

An important feature of the invention consists in the manner by which these eight surfaces in immediate contact with the egg are 30 provided with oblique and rectangular support, so that a shock imposed externally on the container is transmitted to the egg most indirectly, if at all. Wings 16 extend in pairs edgewise in four directions from the 35 axis of the containers, away from the surfaces 10. One pair of these wings is joined to the adjacent edges of two adjacent bearing surfaces, as for example along edges 10^a and 10^b, and joined to each other along the 40 line 16^a, the joint in each case being a fold, and the connection being really integral. Each wing folds downward or outward away from the edge of the bearing surfaces to which it is joined, as seen in Figures 2 and 3. 45 Wings 18 extend from the edges of the upper bearing surfaces 14 as at edge 14^a. Each of these wings folds outward and upward along this edge 14^a and has a more remote and marginal portion 18^a which folds around 50 backward toward itself on line 18^b into alignment with a similar portion of the corresponding wing attached to the other edge of the same bearing surface 14, as seen in Figure 5. The peak of the bearing surface 14 is cut away on an elliptical curve 14^b which cutting continues around the edge of the wing 18 so that when this wing is folded outward on line 14^a its upper end 18^c turns 55 inward over the egg 20, but removed from it a short distance, as shown in Figure 4. Scorings, indicated by dotted lines 18^d, on the wing tips 18^c, cause adjacent tips to curve away from each other, as seen in Figure 5.

The bearing surfaces and wings of the 65 form shown in Figures 2-5 are all integral

parts of a single initial blank which is seen in Figure 1, where the lines other than edges represent creases made in the stock along which the parts are to be folded. The lines 10^a, 10^b and 14^a represent folds convex on the 70 top of the blank, and the lines marked 10^c represent folds convex on the under side of the blank, at which the upper bearing surfaces 14 fold up toward the eye and ultimately inward over the egg. The lines 75 marked 18^b represent folds convex on the top side of the blank along which the portions 18^a of the wings and 18 fold downward, and ultimately outward as already explained. Thus each full line represents a cut edge or a 80 convex fold and each dotted line a concave fold. The double line at 16^b represents a cut. After the blank has been cut and creased as indicated it is preferably crimped to the shape of Figure 2. For this, with 85 stock which requires it, the parts are preferably wetted, then folded as illustrated and placed in a suitable mold which holds it in closed position. I have found that with 90 many kinds of stock this is not necessary. 95 By this or other suitable procedure the stock is given a set or tendency to remain with the surfaces 16 at a concave angle. When dried the stock is removed from the mold and placed in the "flattish" position shown in 100 Figure 2, with the center and extremities of the blank upstanding and with the lower bearing surfaces 10 diverging downward from the central hole. The upper bearing surfaces 14 make a concave angle with the 105 surfaces 10, being supported by the wings 18 whose folded back portions 18^a lie flat on the table. While thus opened many containers may be stacked together, one nesting 110 within another, for shipment. When removed from the stack and laid upon a flat surface, such as a table top, the upstanding center of the container may be pressed gently downward, either by one's finger or by placing the small end of an egg in the opening 12. 115 The downward pressure does not have to proceed very far before the container will reverse its shape and spring or snap into its closed position seen in Figure 3, the lower surfaces 10 coming to make a concavity, and coming into contact with the under part of the egg; and the upper surfaces 14 coming to 120 position close by the upper part of the egg. As shown in Figure 3, the container has snapped to its closed position while empty, and is ready to receive the egg which is preferably entered with its little end downward. This snapping appears to occur because of the set of the surfaces 16 in a relation of concavity. The depressing of the center of the blank from the position of 125 Figure 2 flattens their concavity, and when the dead center or plane position has been passed the concavity can be formed again by the thrusting down of the center which 130

the elasticity of the stock immediately does. The container thus tends to remain in either the position of Figure 2 or Figure 3, and will automatically assume either upon having 5 its centre pushed that way.

Having been thus made "flattish", the container can be placed in a suitable packing box 10 of rectangular shape and of a size to fit the container. Or as shown in Figure 5, a number of the containers can be placed in a single box 22, so as to fill it, each container serving to maintain its neighbors in 15 closed position. The container rests on the edges forming the sides of the central opening 12; and each pair of lower wings 16 stand out with their cut edges 16^a vertical adjoining the side of the box or similar wings of some other container. The top wings 18 press against each other on the diagonal lines of 20 the square, and their folded back portions 18^a stand outside of and may press against the convex side of the fold between 10 and 14, marked 10^c, and against the sides of the box or against similar portions of wings on 25 another container. The top edges of the upper wings all lie in a horizontal plane so that they can bear against the cover of the packing box or can support a flat sheet of paper board placed upon them in case 30 another layer of containers is to be supported thereon. In this way the size of shipment can be varied as desired, a box being chosen which is suited to the quantity of eggs to be shipped.

35 After being once placed in the container the egg need not be removed until it is desired to use it. If inspection is needed, the container can be gripped in the hand and held before a candle, the bottom opening 12 and the opening between the top surfaces 40 enabling the egg to be easily seen, or, if preferred, openings may be provided in the sides, near the fold 10^c, so that the egg can be viewed sidewise through its body. The 45 eggs can be displayed for sale and delivered in their containers. Empty containers can be returned to the packer and used again; although the cost of these containers is so low that they may be wasted if preferred.

50 In Figures 8 and 9 is shown a preferred form of bottom for the container when paper is used. The center of the blank is not cut out, as in the blank of Figure 1, but is left intact and creases *i* and *j* are made, forming two squares one within the other. The 55 creases 16^a are extended in a straight line 16^c through the corners of the outer square to the adjacent corners of the inner square and the creases 10^a and 10^b turn where they 60 reach the sides of the outer square and go perpendicularly along lines 10^a and 10^b toward the sides of the inner square. When the blank is folded the bottom folds inward along the sides *i* of the outer square and the 65 inner square 12^a forms a bottom support for

the small end of the egg. The material between the sides of the squares folds back against the surfaces 10 and against the surfaces of the wings 16, making a double thick border 12^b around the sides of the hollow 70 square and a four ply wall 16^d at the bottom of the wings 16, all of which constitute the base lines of the container.

The modification shown in Figures 6 and 7 illustrates one of many other blanks that 75 may be formed and folded to provide a container embodying various features of the invention. In this type, as in the other described, there are eight surfaces of contact, the four at one end portion of the egg being 80 numbered 24, and those at the other end portion, numbered 26. All are set obliquely and those in each group of four come together at a point at a little distance outside of the adjacent end of the egg. Wings extending 85 in pairs edgewise in four directions from the axis of the container provide rectangular support for the surfaces 24, 26 which are in immediate contact with the egg. These wings extend further than the distance 90 reached by the surfaces themselves, at the corners where they meet each other. This is seen clearly in Figure 7 where the wings which are attached to the upper surfaces are 95 designated 28 and those attached to the lower surfaces are numbered 30. In Figure 6 the full lines represent edges or creases on the blank on which the parts fold away from the eye (convex fold) and the short dash lines represent creases on the under side of 100 the blank, on which the parts bend or fold toward the eye (concave fold). There are openings 34 cut through those parts of the wings which are in line with each other through the mid-portion of the blank and 105 there are also notches 36 in those parts of the wings which are in line with the folds between the surfaces, the said openings and notches permitting the integral stock to bend 110 into the closed form seen in Figure 7.

When the blank of Figure 6 is folded, each part 24 turns up until the edges *b* come together. The portions 30, between the edges *b* and creases *a*, turn downward or away 115 from the eye along the edges *b* and upward or toward the eye along the creases *a*. The portions 38, between the creases *a*, turn upward along the creases *a* and downward along the creases *c* thus nesting between the 120 portions 30. Thus a pyramidal shaped receptacle is formed of the surfaces 24, with each adjacent pair of edges *b* in contact, and with the intervening material 30 and 38 bulged outward and folded double together 125 to form the wings. The edges *a*, and the edges *d*, around the center opening 34, come together as horizontal lines at the bottom of the container, and the edges *a'* come together as vertical lines.

Similarly the parts 26 fold inward, each 130

on its crease *e*, so that the points of these surfaces all come together in the center. The wings 28 which flank each of these surfaces 26 are at the same time folded back and outward on the creases *f* and as the edges of the surfaces 26 come together, each against its neighbor at the crease *f*, the extreme edges *g* of the wings 28 come together in a vertical line in alignment with the vertical lines made by edges *a'*, the wings themselves being flat together. The other edges *h* of these wings 28 come together in horizontal lines, so that like the extreme bottom, the extreme top of the container consists of four double edges extending at right angles to each other. Thus the wings extend to positions outside of the distances reached by any pair of adjacent surfaces and protect the surfaces from contact with the walls of a packing box or receptacle within which the containers may be placed.

The containers may be manufactured by any suitable process; but it is one feature of marked advantage that the process of manufacture can be carried out by machinery by a single operation in which the blank is cut out as represented in Figures 1 and 6 and the various creases placed therein. The folding and crimping may be done subsequently by the shipper of the egg. When a form like Figure 2 has been produced the process is so simple that it can be carried out by merely laying the blank upon a table and depressing it centrally with the point of the egg. The bottom half of the container is thus folded, and the upper half springs into shape and may be readily pressed tightly together by the fingers. When fitted in a packing box the enclosure will be maintained about the egg.

If it should appear desirable, in view of the wide range of size between the smallest and the largest size of eggs found in the market, to manufacture and supply containers of large shell capacity, this can readily be done independently of the packing box by allowing a length of wing projection according to the size of body (shell capacity) of the container. In the case of a very large egg, compared with one of average size, enclosed within a more capacious shell there would be less space (but enough for protection) between its lateral extremities and the walls of the packing box. Any number of body sizes would, by this means, become exchangeable so far as the box was concerned. It is probable, however, that not more than two sizes, of pulp-board material, one for eggs that are small to medium and one for eggs that are medium to large, would be required, taking into account the elastic qualities, heretofore described inherent in the design and material of the container. The preferred material is fibre board, relatively thin, and not too heavy. The thick-

ness of the material is exaggerated in the drawings for clearness of showing.

I claim as my invention:

1. A container for an egg or the like, formed of sheet material and having a multiplicity of oblique surfaces in two groups oppositely arranged, adapted to engage the end portions of the egg, said surfaces being supported at their edges by wings extending outward and adapted to be the primary recipients of shocks, the said wings having edges parallel to and extending alongside of the axis of the egg. 70

2. A container for an egg or the like, formed of sheet material adapted to engage a multiplicity of sides at both ends of the egg and having wings connected integrally with each such engaging surface and extending edgewise outward, guarding the said egg-engaging surfaces from direct contact with exterior objects, the said wings having edges parallel to and extending alongside of the axis of the egg. 80

3. A container for an egg or the like, formed of sheet material having egg-engaging surfaces at both ends of the egg, each surface being substantially tangential to its adjacent egg surface and having supporting wings projecting therefrom in direction away from the axis of the egg substantially at right angles to each other with edges parallel to the axis of the said egg. 90

4. A container for an egg or the like, consisting of a sheet of material having creases radiating from a center that facilitate its being folded from a position in a plane into a position in which a multiplicity of separated portions of the sheet have been moved upward and inward about said central point and the portions intervening between them folded outward and together, the creases between the latter opening oppositely with respect to the creases at edges of the upward and inward moving portions; and there being other creases extending transversely and joining adjacent parts of the last mentioned creases and opening oppositely from them, whereby an enclosing support for one end of the egg is formed, having extensions further foldable to approach each other and enclose the other end of the egg; and means for holding said extensions thus together. 100

5. A container for an egg or the like, comprising a receptacle having creases in its walls whereby it is foldable between an open position and a closed position in which there are interior oblique egg-engaging surfaces and exterior wings extending vertically and laterally in a multiplicity of directions with edges extending alongside the axis of said egg and adapted to be the primary recipients of shocks. 120

6. A container for an egg or the like, comprising a receptacle having creases in its 130

- walls whereby it is foldable between an open position and a closed position in which there are interior oblique egg-engaging yielding surfaces; also exterior wings with edges extending alongside the axis of said egg with edges extending in the same direction as the axis of the egg at a distance from it, said wings extending non-yieldingly in the direction of the axis and non-yieldingly in a multiplicity of directions from the axis and adapted to be the primary recipients and transmitters of shocks.
7. A container for an egg or the like, comprising a sheet whose parts are integrally connected, scored and cut in form to fold into egg-engaging surfaces surrounding both end portions of the egg with points of contact with the egg only at said end portions thereof, and supports projecting laterally from between said engagement surfaces and having outer edges extending in the same direction as the axis of the enclosed egg.
8. A container for an egg or the like, comprising a single sheet having lines marked upon it and adapted to be folded on said lines; said lines being so located that when the sheet is folded thereon separate surfaces formed by the folding can engage an egg tangentially on four sides at one end, and tangentially on four sides at the other end, while other portions, delimited by the said folds, project from the junctions between said tangentially engaging parts in four directions at angles with each other.
9. A container for an egg or the like, formed of elastic and somewhat stiff sheet material, adapted to be approximately flat when in open position and to surround the egg when in closed position; said container, when open, having its center slightly raised and having a multiplicity of egg-engaging surfaces extending outward flatwise from said center and adapted, by pressure downward upon the centre, to spring upward into egg enclosing position.
10. A container for an egg or the like, formed of elastic and somewhat stiff sheet material, adapted to be approximately flat when in open position and to surround the egg when in closed position; said container, when open, having its center slightly raised and having a multiplicity of egg-engaging surfaces extending outward flatwise from said center, with wings joining adjacent edges of said surfaces and forming therewith a pyramidal shaped central portion; said surfaces and wings being adapted to snap past the plane position, upon said center being pressed downward, whereby the surfaces spring upward and inward into egg-enclosing position.
11. A container for an egg or the like, formed of sheet material having egg-engaging surfaces at both ends of the egg, each surface being substantially tangential to its adjacent egg surface; and having supporting wings projecting away from the egg between the egg-engaging surfaces at each end of the egg, with bearing portions, integrally attached, extending toward each other outside of said egg-engaging surfaces and forming a flat bearing surface for the container.
12. A container for an egg or the like, comprising a sheet whose parts are integrally connected, scored and cut in form to fold into egg-engaging surfaces surrounding both end portions of the egg, and supports projecting laterally from between said engagement surfaces, having outer edges extending in the same direction as the axis of the enclosed egg, and having bearing portions attached to said edges and extending in planes substantially parallel with the egg's axis, and forming exterior bearing surfaces for the container.
13. A container for an egg or the like, comprising a sheet whose parts are integrally connected, scored and cut to fold into egg-engaging surfaces surrounding both end portions of the egg; also having supports, projecting laterally from between said engagement surfaces, whose upper parts, extending in the same direction as the axis of the enclosed egg, have inner portions curved over one end of the egg, said inner portions being yieldable to permit insertion of the egg when the container is closed and being adapted to spring back into egg-retaining position after said egg has been so inserted.
14. A container for an egg or the like comprising a rectangular supported egg-enclosing cell adapted to be packed within a box; each cell having interior surfaces arranged for tangential support of the egg, and having exterior bearing portions extending in the direction of the axis of the egg and adapted to rest against the wall of the box and against similar surfaces on an adjacent container.

Signed at Boston, Massachusetts, this fourteenth day of October, 1925.

GILBERT S. FLETCHER.
